UNITED STATES PATENT OFFICE.

JAMES H. REED, OF SWAMPSOFT, MASSACHUSETTS, ASSIGNOR TO A. E. LITTLE COMPANY, OF LYNN, MASSACHUSETTS, A CORPORATION OF MASSACHUSETTS.

SHOE-SEWING MACHINE

Application filed January 22, 1921. Serial No. 439,255.

To all whom it may concern:

Be it known that I, JAMES H. REED, a citizen of the United States, residing at Swampscott, county of Essex, State of Massachusetts, have invented a certain new and useful Improvement in Shoe-Sewing Machines, of which the following is a specification, reference being had therein to the accompanying drawings.

10 My present invention has for its object a new and improved shoe sewing machine intended for use in the manufacture of the novel shoes shown and described in my copending application, Serial No. 439,254
 15 filed January 22, 1921, in which there is a lock stitch seam formed by two threads, the seam being located inside the shoe. Heretofore, in the manufacture of shoes and particularly so-called McKay shoes, the sole has
 20 been stitched to the upper and the insole by a seam located inside the shoe and therefore it has been customary to use a chain stitch sewing machine. The sewing machine embodying my invention sews a lock stitch
 25 seam and has a straight barbed needle, and a shuttle supplying a shuttle thread on one side of the shoe while on the interior of the shoe there is a cooperating horn and an oscillating looper supplying a cop thread.
 30 The horn and looper are of such construction that they can operate in the constricted space inside the toe of a boot or shoe. A take-up for cop thread is also provided, and this is sufficiently powerful to sink the locks
 35 of the stitches to the desired depth in the outsole.

It will be seen from an examination of the drawings that no stitch spreader or loop-forming mechanism is employed for the
 40 shuttle thread and that the shuttle itself, which is of a novel character, performs these functions. This results in great simplification of the machine and consequently in more efficient operation and less expensive
 45 mechanical construction.

While I have shown the machine embodying my invention as constructed for use in sewing the main seams of shoes of the kind described, it is also capable of use in many
 50 other places as for instance for stitching along the shanks on the inside of shoes of the Goodyear welt type, this being a place where the stitching frequently breaks and which it is now customary to stitch by hand
 55 on certain classes of work. While I have

described these two uses for the sewing machine embodying my invention, I do not limit myself to them, as the machine may also be used for other purposes.

The invention will be fully understood from the following description when taken in connection with the accompanying drawings, and the novel features thereof will be pointed out and clearly defined in the claims at the close of this specification.

In the drawings, Fig. 1 is a side elevation partly in section of the machine embodying my invention.

Fig. 2 is a front elevation.

Fig. 3 is a face view of the shuttle.

Fig. 4 is an edge view of the shuttle and shuttle casing.

Figs. 5, 6 and 7 show successive positions of the shuttle and needle, the feed point and presser foot being also shown in Fig. 5.

Figs. 8, 9, 10 and 11 are details showing the different positions of the stitch-forming mechanism.

Fig. 12 is a section on line 12—12 of Fig. 1 showing the take-up.

Fig. 13 is a section on line 13—13 of Fig. 1 showing the take-up operating mechanism.

Referring now to the drawings, there is shown at 11 the base or frame of the machine, at 12 the horn or work support and at 13 the framework of the head. The horn is of a size and shape to render it capable of being inserted in the toe of the shoe and is mounted on the base or frame in such manner as to permit it to be turned as the sewing progresses. At 14 is shown a needle which is straight and barbed. The work which is designated A in the drawings is fed by a feed point 5. At 6 is shown a shuttle which feeds the shuttle thread 7 and has a hook 9 cooperating with the needle in the formation of the stitch. Inside the horn is a looper 8 through which the cop thread 19 is fed and which also cooperates with the needle in the formation of the stitch. A take-up is shown at 20 (see Figures 1 and 12) and operates on the cop thread. All the stitch-forming instrumentalities are actuated by a main shaft 27 rotatably mounted in the framework of the head of the machine.

The needle operating mechanism.

As previously stated, the needle 14 is of the straight barbed type and is mounted on

the lower end of a reciprocating needle bar 21 guided in the frame of the head 13. The needle bar is actuated by a cam lever 22 carrying a cam roll 23 in a cam groove 24 in a 5 plate cam 26 of ordinary construction, as shown in Figures 1 and 2. The cam lever is connected to the needle bar by a link 25. The plate cam 26 is mounted on the main shaft 27 and actuates the needle bar in time 10 with the other working instrumentalities of the machine.

Work feed.

At 28 is shown a presser bar slidable vertically in the head of the machine and carrying at its lower end a presser foot 29 which is secured thereto by screws 30. The work-engaging portion of the presser foot is designated 31 (see particularly Figure 5). The 20 presser bar is held down by the spring 32 and may be lifted up against the tension of the spring to insert the work by means of a lever 33 actuated by a treadle 34 and intermediate connections.

25 In the lower end of the presser bar 28 is formed a slideway in which is located a feed slide 35. The feed slide 35 is actuated by a link 36 pivotally connected at 37 to the lower end of a cam lever 38 actuated by a 30 cam 39 secured to the main shaft 27. The feed slide 35 has pivoted thereto an arm 4 to which is secured the feed point 5. At 42 is shown a spring, one end of which is secured to the feed point arm 4 and the other 35 end of which is secured to the lower end of the presser bar 28. From the foregoing, it will be seen that the feed point 5 has a pawl-like action and slides freely over the work when moved to the left as shown in Figure 5, 40 but when moved to the right will dig into the work and push the work along with it. It will also be seen that the height of the presser bar which varies with the thickness of the work will not affect the action of the 45 feed point.

Shuttle and operating mechanism.

The shuttle 6 is of the discoidal type and is carried by a concentrically disposed annular shuttle case 3. On one side of the shuttle case is a stud 2, as shown in Figure 1, which is engaged by a bracket 10 secured to the under side of the frame 13 of the head. A lever or arm 45 is secured to the stud 2, 55 and extends upwardly terminating in a finger 64 which lies in the path of a cam 65. The cam 65 is mounted on the main shaft 27 and therefore once during each revolution of the main shaft, the finger 64 is pressed back, 60 and the shuttle tilted a little so that the position of the plane of the face of the shuttle relatively to that of the needle is changed and the bottom of the shuttle is brought into the path of the needle, while during the remaining portion of the cycle of movement, the

bottom of the shuttle is back out of the path of the needle. This movement of the shuttle is very slight but assists materially in the formation of the stitch without the use of any loop spreader or other similar mechanisms. The shuttle case is made in two parts 3^a and 3^b secured together by a latch 46 to enable the shuttle to be inserted or removed conveniently. The shuttle is oscillated about its longitudinal axis by a shuttle shaft 47 75 carrying a finger 48 which engages a suitable notch 17 in the back of the shuttle, as shown in Figure 8. The shaft 47 extends rearwardly and is connected with a shaft 49 by means of a sliding universal joint 50. The shaft 49 is mounted in a bracket 51 and carries a gear 52 which meshes with a gear segment 53 formed on one end of an arm 54 pivoted at 55 to the frame of the machine. This arm also carries a cam roll 56 which 80 engages the cam groove of a plate cam 57 mounted on the main shaft 27 of the machine. It will therefore be seen that each rotation of the cam 57 produces a complete 85 oscillation of the shuttle 6 regardless of the angle of its face, the changes in the angle being permitted by the sliding universal joint 50.

The shuttle 6 containing the bobbin for the thread has a flange 58 guided in a groove in the shuttle case 3 so that the shuttle can be rotated by the finger 48 without being displaced. This flange is cut away adjacent the shuttle hook 9 from the point *g* to the point *h* as shown in Figure 3. The hook 9 of the shuttle is of peculiar shape and will be understood by an examination of Figures 3, 4 and 8. The hook 9 is located entirely in front of the plane of the face of the shuttle and extends in a direction circumferentially 95 thereof and substantially concentric therewith. The inside face of the hook 9 is cut away as shown at *d* in Figures 4 and 8 and by dotted lines in Figure 3, to form a groove in which the thread can lie, and to form a recess or clearance for the needle. The shuttle case is cut away on the bottom, as shown at *e* in Figure 4, to form a loop-receiving gap having at one side a projecting point or hook *f* which cooperates with the shuttle hook 9 in throwing the loop and which points in a direction opposite to that of the hook of the shuttle. On the back of the shuttle is a spring tension device 60 secured by rivets 61 to the back of the shuttle. This tension device is a thin sheet of metal notched or slit, as shown at 63. The shuttle thread passes through a hole 64 in the back of the shuttle and thence through the notch 63 in the tension plate 60.

125 It will be understood that in its operation the needle 14 comes up through the work with the loop of the cop thread 19 caught in its barb. When the needle 14 has carried the loop above the point of the shuttle hook 130

- 9, as shown in Figure 5, the shuttle rotates in clockwise direction as indicated by the arrow, and the point of the shuttle hook enters the loop as shown in Figure 6. At 5 this time the shuttle case 3 is tilted to bring the shuttle hook, which at this time is in its lowermost position close to the shank of the needle, so that the point of the shuttle hook will be properly positioned to enter the loop. 10 After the hook has moved a little past the needle, the needle is caused to dip a little, as shown in Figure 7, so that it releases the loop and permits the shuttle hook, which is now moving upwardly from its lowermost 15 position, to lift the loop from the needle hook without cutting or fraying said loop. This movement of the needle is permitted by the cut-away portion *d* previously referred to, as shown in Figures 3 and 8. 20 This rotation of the shuttle carries the shuttle hook 9 toward and past the point *f* of the shuttle case, into and through the loop, as shown in Figure 4, so that these two opposed points cooperate to spread and enter 25 the loop, acting positively to take the latter from the needle hook, insuring the proper entry of the shuttle hook thereinto, instead of merely displacing said loop laterally in removing the same from the needle, and 30 avoiding the necessity of a separate loop spreader for the latter purpose, the use of such a loop spreader having heretofore been found necessary in order to render a mechanism of this type practically operative. At 35 the same time, the end *g* of the rib 58 on the shuttle case passes into the groove in the shuttle case, closing the loop-receiving gap in the latter, and thus the loop is prevented escaping between the shuttle and the shuttle 40 case. It will be seen that at this time, the two legs of the loop are separated from each other by the point of the rib *g* and the point *f* of the shuttle case 3, the inner leg being entirely confined within the shuttle case. 45 The rotation of the shuttle continues until the shuttle hook has passed its uppermost position, and thereafter as the shuttle hook moves downwardly the tension exerted on the cop thread by the take-up, as will be 50 later described, pulls the loop off the right-hand side of the shuttle, as viewed in Figures 5-7, and finally as the shuttle completes its rotation out of the shuttle case through the gap *e* in the side thereof and down upon 55 the work. It will be understood that by this procedure, the shuttle thread has been passed through the loop in the cop thread and the lock of the stitch is formed when the take-up pulls down the stitch. 60 This co-action of the shuttle and needle in forming the stitch without the assistance of a loop spreader or other similar devices results in part from the novel construction of the herein-described shuttle which has its hook formed in front of the plane of its 65 front face, in part from the tilting of the shuttle, and in part from the construction of the shuttle case having a hook which points in the direction opposite to that of the shuttle hook and which assists in opening the loop. All of these important features are believed to be novel. 70
- Horn.*
- The horn 12 is hollow and of elbow shape, 75 being mounted on a hollow base 66 which has a bearing 112 rotatable on the frame of the machine. The horn is not positively rotated, but can be swung by the operator as he sews around the edge of the sole, and the 80 hollow base contains and surrounds a portion of the operating mechanism for the looper and take-up.
- The horn has a flat upper surface 67 forming a work support which is pierced, as 85 shown at *k* and as indicated by dotted lines in Figure 6, to permit the passage of the needle and loop. The work supporting surface of the horn can be made very small to permit its insertion in the toe of a small 90 shoe with as much freedom of movement as is possible under the conditions.
- Looper.*
- The looper 8 is formed on the end of an 95 oscillating shaft 68 carried in bearings in the horn. The looper itself has an eye *n* (see Figures 8 to 10) and therefore is of the thread-feeding type as distinguished from loopers which engage the thread at a certain 100 point of the cycle of operation and are at other times disengaged from it. The looper shaft 68 is drilled longitudinally to provide a passage 69 (see Figure 8), and the thread 105 passes through the passage, then past the bent portion of the looper, then through the eye *n*, and thence through the work. At 70 and 71 (see Figure 1) is shown a pair of bevel gears which connects the lower end 110 of the looper shaft 68 with the proximate end of a shaft section 72 which is at an angle to the shaft 68. This shaft section 72 is also mounted in bearings in the horn 12. The lower end of the shaft 72 is provided with a bevel gear 73 meshing with a gear 74 115 mounted on the upper end of a shaft 75. The shaft 75 has at its lower end, a pinion 76 engaging a rack 77. The rack 77 is connected to a bell crank 78 pivoted at 79 to the frame of the machine. This bell crank is 120 operated by a rod 80 and second bell crank 81, one arm of which is provided with a cam roll 82 operating in the cam groove of a cam 83 on the main shaft 27. From the foregoing it will be seen that the movement produced by the cam 83 causes the looper shaft 68 to oscillate once for each cycle of movement of the machine. 125
- The action of the looper will be readily understood from an examination of Figures 130

8 to 11 inclusive. In Figures 8 and 9, the needle 14 is shown in its lowest position at which time the barb of the needle is below the top of the looper. When the looper oscillates, it passes through the position shown in Figure 9 to the position shown in Figure 10, thereby laying the cop thread in the barb of the needle. Thereafter, when the needle rises, the cop thread 19 is caught by the barb and is carried up through the work forming the loop, as shown in Figure 11.

The construction of the looper is such that it is contained within the hollow end of the horn and can oscillate without interfering 15 with the needle or striking the work from which it is fully protected by the horn. In practice, the horn is cut away, as shown particularly in Figure 8, to make it easier for the operator to thread up the machine, but 20 this cut-away space is not sufficient to permit the shoe to interfere with the movement of either the looper or the needle.

Takeup.—The takeup 20 (see Figure 12) operates on the cop thread and comprises a 25 laterally oscillating finger located in the space between the gears 73 and 74 which operate the looper shaft section 72. It is provided with an eye *m* through which the thread passes. This take-up is pivoted on 30 a vertical shaft 84 located outside the circumference of the bevel gear 74 and inside the circular housing 85 on which the horn is mounted. The shaft 84 is provided at its lower end with an arm 86 having therein a 35 slot 87. This slot receives a pin 88 on an arm 89 of a bell crank pivoted at 90, the other arm 91 being connected by a link 92 to a slide 93. The slide 93 is operated by a bell crank 94 pivoted at 79 (see Figures 1 and 40 13.) The bell crank 94 is operated by a connecting rod 95 connected to one arm 16 of a rock shaft 96, the other arm of which 97 carries a cam roll 98 which travels in the groove of a cam 99 mounted on the main shaft 27.

45 From the foregoing, it will be seen that the takeup finger 20 enters the space between the bevel gears 73 and 74 and is moved out from said space to the position shown in dot and dash lines in Figure 12, drawing the cop thread down vigorously 50 and pulling the lock of the stitch deeply into the channel of the sole.

Certain parts of the machine above described are not claimed herein, being covered per se and independently of the needle by the claims of other applications filed by me as follows:—as to the horn, looper, and takeup; Serial No. 491,694, filed August 12, 1921; as to the shuttle; Serial No. 594,457, filed October 14, 1922; as to the shuttle case; Serial No. 595,266, filed October 18, 1922; and as to the work feeding mechanism; Serial No. 600,224, filed November 11, 1922.

What I claim is:

65 1. A lock stitch shoe sewing machine hav-

ing a straight barbed needle and a shuttle to supply the shuttle thread located on one side of the work, and on the other side thereof a horn pierced at its end for the passage of the needle, and a thread-feeding looper to lay 70 the cop thread in the barb of the needle, said horn being revoluble and said looper being mounted to oscillate therein.

2. In a lock stitch sewing machine, in combination, a straight hook needle located 75 at one side of the work, and at the opposite side of the work a work support having a looper adapted to place a loop in the hook of said needle, means for actuating said needle to draw said loop through the work, 80 a discoidal shuttle and a substantially annular shuttle case therefor located on the same side of the work as said needle, means for turning said shuttle in said shuttle case, said shuttle having a circumferentially extending hook adapted to enter said loop and take the same from the needle hook, and said shuttle case having in its periphery a loop receiving gap of a shape to form on said periphery a point extending in a direction 85 opposite to the hook on said shuttle and adapted also to enter said loop as said shuttle hook is moved toward and past said point, and a takeup for drawing said loop from said shuttle case and down upon the 90 work after said shuttle has passed therethrough.

3. In a lock stitch sewing machine, in combination, a straight hook needle located 95 at one side of the work, and at the opposite side of the work a rotatable horn having a looper adapted to place a loop in the hook of said needle, means for actuating said needle to draw said loop through the work, a discoidal shuttle and a substantially annular shuttle case therefor located 100 on the same side of the work as said needle, and means for turning said shuttle in said shuttle case, said shuttle having a circumferentially extending hook adapted to enter said loop and take the same from said needle hook, and said shuttle case having in its periphery a loop receiving gap of a shape to form on said periphery a point extending in a direction opposite to the hook on 105 said shuttle and adapted also to enter said loop as said shuttle hook is moved toward 110 and past said point.

4. In a lock stitch sewing machine, in combination, a straight hook needle located 120 at one side of the work, and at the opposite side of the work a rotatable horn having a looper adapted to place a loop of thread in the hook of said needle, means for actuating said needle to draw said loop through the work, and mechanism, located 125 at the same side of the work as said needle, for taking said loop directly from the needle hook and passing a locking thread therethrough, said mechanism comprising 130

an outer substantially annular member having a loop receiving gap in its circumference; a concentrically disposed inner thread carrying member, and means for relatively 5 rotating said members about their common center, said members being provided respectively with cooperating opposed points movable toward and past each other into and through said loop to take the latter 10 from said needle hook as said members are relatively rotated, and said inner member having a portion adapted to close the gap in said outer member and confine one leg of the loop within the same until said loop 15 has passed about said inner member.

5. In a lock stitch sewing machine, in combination, a straight hook needle located at one side of the work, and at the opposite side of the work a rotatable horn having a 20 looper adapted to place a loop in the hook of said needle, means for actuating said needle to draw said loop through the work, a discoidal shuttle and a substantially annular shuttle case therefor located on the 25 same side of the work as said needle, said shuttle having a circumferentially extending hook and an annular flange guided on said shuttle case, said flange being cut away adjacent said hook, and said shuttle 30 case having a loop receiving gap in its periphery and a point extending in a direction opposite the hook on said shuttle, and means for turning said shuttle in said shuttle case to cause said hook to move toward and past 35 said point and through said loop to take the latter from the needle hook, and to cause said flange to close the gap in the shuttle case and thereby confine one leg of said loop within said case until said loop has 40 passed about said shuttle.

6. A lock stitch shoe sewing machine including a straight barbed needle, a shuttle,

a shuttle case therefor, means for tilting the shuttle case and means including a universal joint for oscillating the shuttle. 45

7. A lock stitch shoe sewing machine including a straight barbed needle, a shuttle, a shuttle case therefor, means for tilting the shuttle case and means including a sliding universal joint for oscillating the shuttle. 50

8. A lock stitch shoe sewing machine having a straight barbed needle, a shuttle, a shuttle case therefor, said shuttle case being provided with a pivotal mounting at right-angles to its axis of rotation, a finger 55 secured to said pivotal mounting, means for moving said finger to tilt said shuttle case in proper timed relation to the other working instrumentalities, and means for oscillating said shuttle including a universal 60 joint.

9. In a lock stitch sewing machine, in combination, a straight hook needle located above the work, a rotatable horn located below the work and having a looper adapted 65 to place a loop in the hook of said needle when said needle is in its lowermost position, means for actuating said needle to draw said loop through the work, a discoidal shuttle above the work and rotatable about 70 an axis transverse to the path of movement of the needle, said shuttle having a circumferentially extending hook which in its lowermost position is adjacent the uppermost position of the needle hook, and means for 75 turning said shuttle about its axis to cause said shuttle hook to lift said loop from said needle hook, said needle actuating mechanism operating to dip said needle coincidentally with the upward movement of said 80 shuttle hook.

In testimony whereof I affix my signature.

JAMES H. REED.
